UNITED STATES PATENT OFFICE.

FLORENCE L. ROBERTSON, OF FERGUS FALLS, MINNESOTA.

STOVE COVER.

Application filed September 20, 1921. Serial No. 501,944.

To all whom it may concern:

Be it known that I, FLORENCE L. ROBERTSON, a citizen of the United States, residing at Fergus Falls, in the county of Otter Tail and State of Minnesota, have invented certain new and useful Improvements in Stove Covers, of which the following is a specification.

This invention relates to attachments for 10 oil and gas stoves and more particularly to covers therefor.

The object of the invention is to provide a cover of this character which performs the double function of a protector for the 15 walls when cooking and for the stove when the latter is not in use.

Another object is to provide a cover of this character constructed so that when closed it will completely encompass the 20 stove top and be held out of contact with the burner grate protecting them from dust, etc., and the outer face of which presents a smooth surface for use as a table.

Oil and gas cook stoves, which have no 25 backs, and which usually must be located near a wall are objectionable owing to the fact that the grease when cooking splashes on the wall and adjacent objects and it is to overcome these objections that this invention 30 is designed.

With these and other objects in view, the invention consists in certain novel features of construction as hereinafter shown, described and claimed.

35 In the accompanying drawings:—

Figure 1 represents a front elevation of the upper portion of a cook stove with this improved cover shown applied and in raised position.

40 Fig. 2 is a top plan view thereof, and,

Fig. 3 is an end elevation, with parts broken out and in section.

In the embodiment illustrated, a gas stove top 1 is shown equipped with the usual depending peripheral flange 2 and burners 3. The top 1 is provided at one end thereof adjacent the depending flange 2 with a transversely extending slot 4, for a purpose presently to be described.

45 The cover 5 constituting this invention is shaped to conform to the top 1 of the stove, being here shown rectangular, and is provided with a circumferentially extending right angularly disposed inturned flange 6, the free edge of which is designed to rest 50 on the upper face of the top 1 of the stove

adjacent the flange thereof and hold the body portion of the cover 5 spaced above the burners 3. This cover 5 is hinged at 7 to the rear edge of the stove cover 1 and 60 a link or iron strap 8 is pivotally connected at one end to one end of the cover 5 midway the width thereof, while its other end is notched, as shown at 9, and is adapted to extend through the slot 4 in the top 1 and 65 the notch to engage the rear wall of said slot to hold the cover 5 in upright open position as is shown clearly in Fig. 3.

It will thus be seen that the cover 5 when in lowered position protects the burners 3 70 against dust, dirt and the like, and when opened and swung to the position shown in the drawings will be held by the brace or link 8 and protect the wall at the rear of the stove against the splashing of the grease 75 thereon.

Vapor stoves equipped with warming ovens, shelves, backs and the like, are much 80 more expensive than the plates such as that shown in the drawings and yet when the plates are equipped with the covers herein 85 shown and constituting this invention, will have all of the advantages of a stove equipped with a fixed back, and the back will have additional advantages owing to 90 the fact that the lowering of this cover over the burners protects them when the stove is not in use, as well as providing a table which is especially desirable in small 95 kitchens and yet is comparatively inexpensive to manufacture.

While the cover 5 is shown connected with the top 1 by strap hinges in the accompanying drawings, obviously any other form of hinge may be provided.

100 The preferred embodiment of the invention is disclosed in the drawings and set forth in the specification, but it will be understood that any modifications within the scope of the claimed invention may be made in the construction without departing from the principle of the invention or sacrificing any of its advantages.

What I claim is:—

105 The combination with a stove top provided with a continuous outwardly flared depending flange and further provided with a transverse slot in proximity to one side of said flange, of a cover having a vertically disposed continuous flange conforming in 110 contour to the shape of said top and adapted to have its lower edge seat on the upper

edge of said flared flange when the cover is closed, means for hinging the rear portion of the flange of the cover to the rear portion of the flange of the top, and a supporting element permanently extending through said slot and having its upper end pivoted to the inner face of one side of the flange of the cover, said element provided

with means near one end for detachably engaging with one end wall of the slot for maintaining said element extended to support the cover at right angles with respect to the rear of the top.

In testimony whereof, I affix my signature hereto.

FLORENCE L. ROBERTSON.
